CLAMP FOR PLACING WELL CASINGS

Filed Oct. 1, 1946

FIG. 1.

FIG. 2.

FIG. 3.

Aubrey Trotter, Inventor,
By Frank S. Appleman, Attorney.

UNITED STATES PATENT OFFICE

2,450,388

CLAMP FOR PLACING WELL CASINGS

Aubrey Trotter, Lafayette, La.

Application October 1, 1946, Serial No. 700,441

2 Claims. (Cl. 24—249)

1

This invention relates to means for holding drill pipe and well casings during a drilling operation whereby the said casings may be held while an operator is preparing to supply successive lengths of drill pipe and well casings as the drilling progresses, and it is an object of this invention to provide a clamp which will hold a well casing or pipe while the derrick man is on his platform and while the pipe is about to be applied to a hole being drilled, and it releases the pipe as the elevators are traveling with relation to the clamp, as by the use of this invention the hands of the derrick man are left free for other manipulations and the derrick man is not subjected to danger which might otherwise be incurred if the pipe were not securely held in place.

An object of this invention furthermore is to provide an attachment which is applicable to a monkey board of a derrick, and novel means are provided for holding a pipe section while the elevator is operated, and the said invention comprises comparatively few, inexpensive parts which have proven efficient and satisfactory in use, as the clamp operates to hold the pipe and of course the device may be made in different sizes for operation on pipes of different diameters within the range of those usually employed in well drilling, it having been stated by the inventor that it may be used on 2 inch to 8 inch pipes and proves efficient in any of the sizes.

A further object of this invention is to provide a clamp having arms, one of which is stationary and the other of which is oscillatively mounted; and the invention furthermore provides for a latch removably secured to the movable arm and so mounted that it may be actuated by the foot of an operator for causing the engagement of the latch with the movable arm, or for disengaging the latch therefrom, so that when the latch is holding the arm, the jaws of the clamp engage and hold a pipe section.

A still further object of the invention is to provide novel means for mounting the clamp on the monkey board whereby it is movable to change its location with respect to the hole or drilling operation.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like char-

2

acters denote corresponding parts in the several views, and in which—

Figure 1 illustrates a plan view of a clamp and its installation embodying the invention;

Figure 2 illustrates a view in elevation of the end of the clamp having the latch applied to it; and

Figure 3 illustrates a sectional view on the line 3—3 of Fig. 1.

In these drawings 1 denotes the platform on which the device is installed, 2 denotes a stationary arm which is rigid with a plate having spaced lugs or ears 3 and 4, and 5 denotes a latch which has an end 6 projecting over an extension 7 of the plate, and a spring 8 is interposed between the extension of the plate and the end 6 of the latch and is operative to exert upward pressure on the end of the latch so that the nose or lug 9 of the latch will engage an arm 10 of the clamp, it being shown that the clamp has jaws 11 and 12 which are integral with the arms 2 and 10, respectively. The said arm 10 crosses the arm 2 and is oscillatably connected to it by a pivot 13, which pivot extends through a slot 14 of a plate 15 which is attached to the platform or monkey board by fastenings 16, such as screws or the like.

As has been stated, the clamp is adjustable with relation to the plate 15 so that the clamp may be aligned more nearly with the drilling operation.

It is obvious from the description and illustration that when the movable arm 10 is oscillated to separate the clamps, a pipe may be interposed between the jaws thereof, and when the movable arm is operated to cause engagement of the jaws with the pipe, the latch can be pressed down so that the lug 9 engages or partially embraces the arm and it will be held in this position with the clamp holding the pipe, this being due to the action of the spring 8 which normally presses the outer end of the latch upwardly. When the pipe is to be released, foot pressure on the extended portion 6 of the latch will elevate the latch out of engagement with the arm, and the pipe is then freed for its transfer by the usual elevating mechanism.

45 I claim:

1. A clamp for placing well casings, a slotted base member adapted to be secured to a derrick platform, a pivot slidable in the slot, an arm secured to the pivot and having an integral pipe-50 engaging jaw, an anchoring plate to which the arm is connected, a movable arm oscillatable on the pivot and having a jaw cooperating with the first mentioned jaw, a latch extending transversely of the arms near their ends, means for pivotally connecting the latch in association with the sta-

tionary arm, the said latch having a lug engaging the movable arm and operative to hold the clamp in closed position, and a spring engaging the latch for holding the lug in engagement with the movable arm.

2. A clamp for placing well casings, a slotted base member adapted to be secured to a derrick platform, a pivot slidable in the slot, an arm secured to the pivot and having an integral pipe-engaging jaw, an anchoring plate to which the arm is connected, a movable arm oscillatable on the pivot and having a jaw cooperating with the first mentioned jaw, a latch extending transversely of the arms near their ends, means for piv-

otally mounting the latch on the anchoring plate whereby one end of the latch extends beyond the pivot, a spring interposed between the extended end of the latch and the anchoring plate for holding the latch normally operative, the said latch having a lug engaging the movable arm and operative to hold the clamp in closed position, the said clamp being operative by foot pressure to force the latch in engagement with the movable arm and also operative by foot pressure on the end of the latch to release the latch from the arm.
